UNITED STATES PATENT OFFICE.

HENRY ROSS, OF NEW CASTLE, PENNSYLVANIA, ASSIGNOR TO AMERICAN CAN COMPANY, OF NEW YORK, N. Y., A CORPORATION OF NEW JERSEY.

SHEET-METAL PUTTY-CONTAINER.

No. 911,163.

Specification of Letters Patent.

Patented Feb. 2, 1909.

Application filed September 26, 1908. Serial No. 454,877.

To all whom it may concern:

Be it known that I, HENRY ROSS, a citizen of the United States, residing in New Castle, in the county of Lawrence and State of Pennsylvania, have invented a new and useful Improvement in Sheet-Metal Putty-Containers, of which the following is a specification.

My invention relates to improvements in the construction of sheet metal packages for shipment and storage of putty or other like materials.

The object of my invention is to provide a sheet metal putty package of a simple construction, capable of being cheaply manufactured, and which will be light in weight and have a strong, efficient and durable construction.

My invention consists in a sheet metal vessel or package having a double body, the inner and outer walls of which are united to a single bottom head at the lower end, the inner wall by an external folded or double seam and the outer wall by turning or folding its lower edge around the double seam which unites the inner wall to the bottom head, the two walls of the double body being folded or rolled together at their upper ends, and further braced and locked together by interengaging beads which are made inwardly projecting to form a shoulder for the upper head of the package, which is preferably of wood and secured in place by nails extending through the double wall body at the mouth portion thereof.

The invention further consists in the novel construction of parts and devices and in the novel combinations of parts and devices herein shown and described and more particularly specified in the claims.

In the accompanying drawing forming a part of this specification, Figure 1 is a central, vertical sectional view of a double body, single bottom, tapering, sheet steel putty package embodying my invention. Fig. 2 is a horizontal section on line 2—2 of Fig. 1. Fig. 3 is an enlarged detail vertical section.

In the drawing, 1 represents the single bottom head of the vessel. 2, the double body and 3 the cover. The single bottom head 1 has a countersink wall 4, fitting snugly within the lower end of the double body and a seaming flange 5, which is interfolded with the corresponding seaming flange 6 of the inner wall 7 of the double body into an externally folded or double seam 8. The

outer sheet metal wall 9 of the double body 2 is furnished at its lower end with an inwardly projecting inturned flange 10 and an upturned flange 11 embracing the double seam 8 which unites the inner wall 7 of the double body to the bottom head 1. The inner wall 7 is preferably composed of a plurality of pieces united by a plurality of lock side seams 12, and the outer wall 9 of the double body is likewise preferably composed of a plurality of pieces united by a plurality of lock side seams 13, which project between and separate the two walls of the double body.

At their upper ends, the inner and outer sheet metal walls 7 and 9 of the double body 2 are rigidly and firmly secured together by externally projecting rolls or folds 14 and 15, the roll 14 on the inner sheet metal wall 7 embracing the roll 15 on the outer sheet metal wall 9. The two walls 7 and 9 of the double body are further securely locked and braced together by internally projecting beads 16 and 17 which snugly engage each other, said internally projecting beads also forming a shoulder for the inside fitting head 3 of the package to rest upon. This cover head 3 is preferably of wood, and is secured in place, preferably by wire nails 18, inserted through suitable openings 19 in the mouth portion 20 of the double body 2, at which mouth portion the two walls of the double body fit snugly together. The outer sheet metal wall 9 of the double body 2 is preferably provided with a series of annular corrugations 21 to further stiffen and strengthen the same.

I claim:

1. The sheet metal putty package herein shown and described, and comprising a single bottom head and a double tapering body having its inner and outer walls united to said single bottom head at their lower ends, and its inner and outer walls interfolded and united together at their upper ends, and also provided near their upper ends with interengaging internally projecting beads to form a shoulder for an inside fitting cover to rest upon, and an inside fitting cover fitting and secured within the mouth of the vessel, substantially as specified.

2. In a sheet metal vessel, the combination with a single bottom head, of a double body having its inner wall interfolded at its lower end with said bottom head, and its outer wall provided with a flange embracing the seam

uniting said inner wall and bottom head, said inner and outer walls of said double body being interfolded and united at their upper ends, substantially as specified.

- 5 3. In a sheet metal vessel, the combination with a single bottom head, of a double body having its inner wall interfolded at its lower end with said bottom head, and its outer wall provided with a flange embracing
10 the seam uniting said inner wall and bottom head, said inner and outer walls of said double body being interfolded and united at their upper ends, and also provided near their upper ends with interengaging beads,
15 substantially as specified.
4. In a sheet metal vessel, the combination with a single bottom head, of a double body having its inner wall united at its lower end by a double seam to said bottom
20 head, and its outer wall furnished with inwardly and upwardly projecting flanges embracing the seam uniting said inner wall and said bottom head, said inner and outer walls of the double body having at their upper ends
25 externally projecting interengaging rolls securing said walls together, and said inner and

outer walls of the double body having inwardly projecting interengaging beads to further brace and lock said walls together, substantially as specified.

30 5. In a sheet metal vessel, the combination with a single bottom head, of a double body having its inner wall united at its lower end by a double seam to said bottom head, and its outer wall furnished with inwardly 35 and upwardly projecting flanges embracing the seam uniting said inner wall and said bottom head, said inner and outer walls of the double body having at their upper ends externally projecting interengaging rolls 40 securing said walls together, and said inner and outer walls of the double body having inwardly projecting interengaging beads to further brace and lock said walls together, and an inside fitting wood cover resting 45 upon the inwardly projecting bead of the inner wall of the double body, substantially as specified.

HENRY ROSS.
